No. 186

Robert Wood designs of William Hamilton
Simpson Designs for His Table
Dated June 20, 1818.

2 sheets sheet 2

D 186

Robert Wood and Wm Hamilton.

Philadelphia County, Pennsylvania
Letter Patent No 186, dated June 20th 1848
(assigned to R Wood)

The schedule referred to in these letters Patent and making part of the same

to whom it may concern.

It is known that Mr Robert Wood & Wm Hamilton both of the County of Philadelphia in the state of Pennsylvania have invented or produced a new and useful design for a cast iron pier & centre table and to hereby declare that the following is a full and exact description of the same.

Plate 1 Fig 1 represents one of the uprights or standards for the Centre Table, at the bottom it represents a dolphin with its tail entwined with foliage and scroll work as marked on Fig 1 at a, connected with the above are piped scroll work with a fluted edge; all of which terminates with foliage and small scrolls festooned with flowers and leaves delineated at B.B.

at the top are two connecting branches of coving and piped scroll work with a row of holes as marked at C, three of the above described standards or brackets connected by the pillar or centre support represented at fig 3, together with the rim represented at fig 2, forms the stand for the centre table.

Two of them reversed as represented at Plate 3 fig 1 connected at the points where they would be to the centre pillar for the centre table, forms the standard for the side table.

Fig 5 represents the inside or back of one section of the rim for the support of the top of the centre table, the same being composed of four sections each section being divided into two parts of a circle or oval as shown at fig 2, the ornament on the edge of the same is a continued egg moulding with a square at the top as represented in perspective at D.

Fig 3 represents the pillar or centre support of the centre table, the top of the pillar is octagon as at a supported by a round coving & square represented at b, which is supported by a fluted shaft with an oval ornamented with reeds represented at cc, below which is a cove & square represented at d, below which is again continued the octagon, from which drops 4 lines over a cove & square represented at e below which terminates the octagon. The whole pillar is shown more distinctly at f in perspective and is completed by

Fig 4 This represents the drop ornament as shown at f in perspective, the rim at the top

is intended to screw into the bottom of the jib
bar fig. 3, the top or base of the drop commu-
nies with a square as at a, below which is a squat
cone as at b, below which is 6 plain leaves as
at c, below which is a square and cone termin-
ated with points as at d, the whole drop
being completed by the half of an elongated
globe.

Plate 2 fig. 2 represents the brace or stretcher
of the Pier Table. The bottom of the stretcher
represented by a lead at D, D, D, D, resting on which
in the centre is a vase of flowers and fruit represent-
ed at b the vase being ornamented by clustering the
foot being formed of leaves and resting on the
lead D, from the vase extend each way along
the stretcher are branches of light foliage alter-
nated with flowers berries and piped scroll
work as represented at f f f which completes
the stretcher.

Plate 2 fig. 1. Represents the pier table in per-
spective in which will be seen the arrangement
of the standard which is particularly described
under plate 1 fig. 1 also the position of the brace
described under plate 2 fig. 2 and their relative posi-
tions together in the pier table.

We have thus described the several parts of the orna-
ments for the pier & centre tables which we wish to
Patent and the general arrangement of each and
of hereby claim the exclusive right to the orna-
mental designs as we have arranged and display-
ed them in the pier & centre tables.

And witnesseth

John M. P. Goffon

Robert Wood
